Primary Examiner — Kelley A Donnelly**CLAIM**

The ornamental design for a rotating display, as shown and described.

DESCRIPTION

FIG. 1 is a front elevation view of a first embodiment of the rotating display, rear elevation view being a mirror image thereof;

FIG. 2 is a right side elevation view of a first embodiment of the rotating display, left side elevation view being a specular image thereof;

FIG. 3 is a perspective view thereof;

FIG. 4 is a second perspective view thereof;

FIG. 5 is a perspective view thereof with a rotated module; and

FIG. 6 is a top plan view thereof;

FIG. 7 is a front elevation view of a second embodiment of the rotating display, rear elevation view being a mirror image thereof;

FIG. 8 is a right side elevation view of a second embodiment of the rotating display, left side elevation view being a mirror image thereof;

FIG. 9 is a perspective view thereof;

FIG. 10 is a perspective view thereof with rotated module; and,

FIG. 11 is a top plan view thereof.
